SPARK PLUG

Julius Devine, New York, N. Y.

Application February 25, 1937, Serial No. 127,610

5 Claims. (Cl. 123—169)

This invention relates to spark plugs and particularly to spark plugs of the type capable of producing proper ignition in internal combustion engines of the relatively high compression class.

5 An object of the invention is to provide a new and improved spark plug of relatively great durability by reason of the incorporation therein of a novel combination and interrelation of parts producing a unit which is capable of withstanding the 10 highest temperatures and compressions encountered under the most trying operating conditions.

Another object of the invention is to provide in a spark plug of the type in which one of the 15 electrodes is in the form of a centrally disposed pin, or spindle, novel means for insuring a gas tight joint around said spindle.

These and other objects of the invention will be apparent to those skilled in the art from the 20 following description, taken in connection with the accompanying drawing wherein are illustrated two embodiments of the invention. It is to be expressly understood, however, that the drawing is for the purpose of illustration only and is not 25 designed as a definition of the limits of the invention, reference being had for this purpose to the appended claims.

Referring to the drawing:

Fig. 1 represents a spark plug in longitudinal 20 central section.

Fig. 2 a view taken on 2—2 of Fig. 1.

Fig. 3 is a section of the filler.

Fig. 4 is a view of the grooved head of spindle.

Fig. 5 is a section of a modified form of spark 35 plug.

Fig. 6 shows the steel collar and brass wedge.

Fig. 7 shows the steel wedges.

Referring now to the drawing wherein like reference characters indicate like parts throughout the several views. In the form shown, the plug comprises a shell 10, exteriorly threaded as at 11 for threaded engagement with an opening in a cylinder wall of an internal combustion engine in the usual manner. The upper part of the 45 shell 10, is internally threaded as at 12 and is of larger diameter than the lower part so as to provide an inner shoulder 13.

A gasket 14 is placed on the shoulder 13.

The positive electrode comprises a metallic 50 spindle 15, having at its lower end an enlarged head 16, which carries a spark gap point 17. An insulator 18, preferably mica sleeves surrounds electrode 15, preferably throughout its length, resting at its lower end on the head 16. A plurality of insulating washers 19, preferably of mica,

surround the lower portion of electrode 15, and insulating sleeves 18 adjacent to the head 16, said washers preferably being of increasing outer diameter away from said head 16.

The construction of the head 16 is as follows: 5 Around the spindle 15, there is provided a groove 20 with an upstanding rim 21. When the insulation 18 is placed around the spindle it is projected into the groove 20. The space between the insulation 18, and the rim 21 is occupied by a filler 22, to be described hereafter but whose function is to keep the bottom of the insulation 18, gas tight, that is, to prevent any gas entering between the insulation 18, and the spindle 15.

The filler 22 may be any one of a number of 15 articles that can be used, such as solder, cement, or a soft metal as a brass wedge 23, may be forced in and hammered in till it fills the groove 20. The outside of the rim may be forced inwards by pressure so as to completely fill the groove. 20

On top of the insulating washers 19, there is seated a gland 27, externally threaded as at 28, for engagement with the screw threaded portion 12, and surrounding the intermediate portion of electrode 15, and insulating sleeves 18. The 25 gland 27, is provided with an inclined bottom portion 30, the surface of which conforms in slope to shoulder 13, of the shell 10.

The gland 27, is made of steel just soft enough so that the center of which may be worked, that 30 is the gland 27, has a portion removed from its top forming a circular triangular void 31, a thin wall 32 is left adjacent the spindle 15 and insulation 18. If desired a similar portion may be removed from the bottom of the gland 27 forming 35 a circular triangular void 33, with a corresponding thin wall 35.

Hard steel wedges 36 and 37 somewhat larger than the voids 31, and 33, are adapted to be forced into the voids thereby forcing the soft 40 steel walls 32, and 35, tightly against the insulation 18, and thereby providing a gas tight seal around the electrode 15. Either one or two wedges may be used.

The shell 10 is provided with an inclined electrode 38 projecting into the proper spaced relationship to the center electrode 15, and spark point 17. 45

A plurality of other insulating washers 39 are provided resting on a washer 40, which is superimposed on the gland 27 and surrounding substantially the remaining upper portion of electrode 15, and insulating sleeves 18, said washers 50 preferably decreasing in diameter toward the top of electrode 15.

A resilient cap 41 of brass and a washer 42 of asbestos being inserted between the outer end of the mass of mica washers 39, and the terminal nut 43, which is in threaded relation with the upper end 44 of the electrode 15.

A binding post 45 is provided to tighten wires (not shown) to the plug.

In Fig. 5 there is illustrated another embodiment of the present invention. In this form the 10 gland 46 has its inner center cut with two opposing inclinations 47-48 coming to an apex towards the middle of the gland. Wedge rings 36, 37 are placed within the inclinations 47, 48 but not touching each other. A soft metal tube 15 49, is placed against the insulating material 18 right behind the wedge rings 36, 37 so that when the wedge rings are taken up or forced against each other, the soft metal tube 49 will prevent the piercing of the insulating sleeves 18.

20 In the modification the spindle head 16' is provided with a shoulder on which the insulation sleeves rest. The seal at this point is made by placing over the spindle and insulation 18 a steel collar 50 the upper portion of which is flat 25 or uniform thickness and lower portion having an internal outward inclination 51. A brass wedge ring 52 having an outside inward inclination 53 but longer than the inclination 51 of the steel collar. This brass wedge 52 is placed 30 underneath the steel collar 50 and allowed to project somewhat below the collar 50.

The seal is made tight by forcing the collar 50 downwards and thus squeezing the brass ring 52 against the insulation 18 and spindle 15.

35 There is thus provided an improved spark plug structure which is rugged and strong both mechanically and electrically and which is compactly and easily assembled from a small number of parts. Due to its simplicity, it is also 40 cheap to manufacture. Novel means are provided in this spark plug for effectively preventing the escape of gases from the engine cylinder, through the spark plug structure, and thus decreasing the loss of compression, as well as pro- 45 longing the life of the plug.

It will be obvious that the invention is not limited to the specific forms described and illus-

trated in the drawing but is capable of a variety of mechanical embodiments. Various changes, which will now appear to those skilled in the art, may be made in the form, details of construction, and arrangements of parts without departing from the spirit of the invention. Reference is therefore to be had to the appended claims for a definition of the limits of the invention.

What I claim is:

1. In a spark plug, a gland, a spindle, insulation between said spindle and said gland, said gland having a portion removed therefrom leaving a thin sleeve against the insulation, a wedge ring adapted to be forced into the removed portion and forcing the sleeve against the insulation. 15

2. In a spark plug, a gland, a spindle, insulation surrounding said spindle, a sleeve of soft metal against the insulation and a pair of separated opposite acting wedges acting on the 20 gland to force the soft metal sleeve against the insulation.

3. In a spark plug, a spindle, insulation surrounding said spindle, a gland surrounding said insulation and comprising inner and outer 25 portions connected together at approximately the center thereof and means for forcing the inner portions against the insulation.

4. In a spark plug, a spindle having an enlarged head and a groove formed within said head around the spindle, an insulation sleeve surrounding said spindle and projecting within said groove, a filler adapted to firmly seal the portion between the insulation sleeve and the outer face of the groove, said filler comprising a brass conical ring which is forced to fill the said portion. 30

5. In a spark plug, a gland, a spindle, insulation between said spindle and said gland, a soft metal sleeve surrounding said insulation, said gland being cut on its inside with two opposing 40 wedge surfaces coming to an apex at about half way its height, two opposing steel wedge rings adapted to be forced into the space between the wedge surfaces and the soft metal sleeve for tightening the sleeve around the insulation. 45

JULIUS DEVINE.
